[57] CLAIM

The ornamental design for a candle box, as shown and described.

DESCRIPTION

FIG. 1 is a perspective view of a candle box showing my new design;

FIG. 2 is a front view thereof, the rear view being identical; FIG. 3 is a left side view thereof, the right side being identical; and,

FIG. 4 is a top view thereof.

The bottom view is omitted as it does not form part of my claimed design.
